UNITED STATES PATENT OFFICE.

EDWIN L. GILES, OF LOWELL, MASSACHUSETTS.

SWITCH FOR STORE SERVICE.

SPECIFICATION forming part of Letters Patent No. 333,744, dated January 5, 1886.

Application filed June 5, 1885. Serial No. 167,759. (No model.)

To all whom it may concern:

Be it known that I, EDWIN L. GILES, a citizen of the United States, and a resident of Lowell, Middlesex county, Massachusetts, have invented certain new and useful Improvements in Switches for Store-Service, of which the following is a specification.

My invention relates to that class of store-service apparatus in which the ways are traversed by rolling carriers of different dimensions; and my invention consists in combining with the said ways and with a rail forming a continuation of the main track a deflector above the ways, whereby the larger carriers are directed over the said rail and onto the branch track.

In the accompanying drawings, Figure 1 is a perspective view illustrating my improved deflector as arranged at the junction of the main and branch tracks of a store-service railway; Fig. 2, the same showing the parts in a different position; Fig. 3, a plan of Fig. 2; Fig. 4, a longitudinal elevation illustrating a modification.

A represents the main and B the branch track of the way of a store-service apparatus; but the branch track, instead of opening into the main track, as usual, is closed by a rail, a, of the main track, so that the latter is practically continuous, and carriers, in the shape of hollow spheres X, moving in the direction of the arrow, Figs. 2 and 3, will be maintained upon the main track, and can only be transferred to the branch through the medium of proper appliances. Inasmuch as some of the carriers only should travel continuously upon the main track, I provide means whereby those which should be transferred to the branch track shall be caused to cross the rail a, such means consisting of a deflecting bar or wing, D, and appliances for bringing it in position to be struck by the carriers to be deflected, and to guide the latter off the rail A onto the branch track, the said appliances being of such a character as to be operated to adjust the bar by the carriers which have to be transferred.

Different means for operating the bar may be employed. I have shown in the drawings one which has proved effective. The bar, as shown, consists of a bent rod secured to a shaft,

b, turning in bearings upon a standard, d, secured near the junction of the two tracks, and in a bracket, d', supported by a yoke, E, enclosing and overhanging the main track. By 55 rocking the shaft b the deflector may be elevated to such a position as to be out of the way of all the carriers, as shown in Figs. 2 and 3; or it may be turned down so as to be struck by such of the carriers as are in excess of a 50 certain size and guide them laterally over the rail a, over the track B, as shown in Fig. 1. The automatic rocking of the shaft b is effected by the vibration of an arm, f, projecting from a rock-shaft, g, turning in bearings in the yoke 65 E, the arm f projecting under a weighted arm, h, extending from the shaft b. When the arm f is thrown upward, the shaft b is turned and the deflector is carried downward to the position shown in Fig. 1, and when the arm f is 70 carried downward the weight upon the arm h turns the shaft b and lifts the deflector to the position shown in Fig. 2.

The movements of the shaft g requisite to adjust the deflector are effected by the carriers through the medium of a pendent arm, k, which is threaded and extends through a hub in the shaft g, and may be turned to adjust the arm to any desired position, so as to be struck by the larger carriers which are to be 80 deflected. The smaller carriers pass beneath the arm k, and are maintained upon the main track. The larger carriers, by striking the arm k, rock the shaft g and adjust the deflector so as to be struck by the carriers.

The rail a is preferably depressed or sunken opposite the center of the track B, to facilitate the transfer of the carriers, and it may consist of a wire, as shown, or it may be a continuation of the inner rail, m, of the main track.

I have shown devices in Figs. 1, 2, and 3 to illustrate the adjustment of the deflector; but I wish it to be understood that I do not limit myself to this means of altering its position above the tracks. For instance, it may be secured to sliding bars n n, extending through parts of the track or through brackets connected therewith, and these bars may be connected to crank-levers H, the vibration of which is the means of raising and lowering the 100 bars and altering the position of the deflector, as shown in Fig. 4. The devices for impart-

ing motion to the deflector from the carriers may also be differently constructed from those shown in Figs. 2 and 3. For instance, levers N N' may be connected to the levers H H, and 5 may be arranged between the tracks to be struck by the carriers, as illustrated in Fig. 4, so as to swing the levers H, the levers N N' only being acted upon by the smaller carriers, which sink to a greater distance below the 10 surface of the rails.

It is not essential that the deflector shall in all cases be adjustable. It may be secured in its position fixedly above the tracks, so as to permit the smaller carriers to pass along the 15 main track and to be struck by the larger carriers.

Without limiting myself to the precise construction and arrangement of parts shown, I claim—

20 1. The combination, with the main and branch tracks of a store-service apparatus, of a rail extending across the branch track where it connects with the main track, and an adjustable deflector arranged to be struck by graduated carriers and to guide the latter over the 25 said rail to the branch track, substantially as set forth.

2. The combination, with the main and branch tracks and deflector arranged above 30 the tracks, of a rail extending across the branch

track at its junction with the main track, and depressed, substantially as and for the purpose set forth.

3. The combination, with the main and branch tracks, of an adjustable deflector and 35 appliances, substantially as described, for moving the deflector by the action of graduated carriers, for the purpose set forth.

4. The combination of the main and branch tracks, rail *a*, deflector hung to supports 40 above the tracks, and rocking arm arranged to be struck by graduated carriers, and connections between the arm and the deflector, substantially as described.

5. The combination of the main and branch 45 tracks and rail *a*, and a deflector hung in bearings above the tracks, provided with a weighted arm, a rock-shaft hung above the tracks and provided with an arm extending under said weighted arm, and with a pendent arm 50 arranged to be struck by the larger carriers, substantially as described.

In testimony whereof I have signed my name to this specification in the presence of two subscribing witnesses.

EDWIN L. GILES.
